Specification for Design.

Patented Mar. 15, 1921.

Application filed August 27, 1920. Serial No. 406,485. Term of patent 7 years.

To all whom it may concern:

Be it known that I, MAUDE HAMILTON, a citizen of the United States, residing in the city of Seattle, in the county of King and State of Washington, have invented a new, original, and ornamental Design for a Boudoir-Receptacle, of which the following is a specification, reference being had to the accompanying drawings, forming a part thereof.

Figure 1 is a perspective view in front and end elevation of my boudoir receptacle; and

Fig. 2 is a perspective view in rear and end elevation of the same.

What I claim is:

The ornamental design for a boudoir receptacle as shown.

MAUDE HAMILTON.
